UNITED STATES PATENT OFFICE.

HOWARD H. HILL, OF MONTCLAIR, NEW JERSEY, ASSIGNOR OF ONE-HALF TO MAXWELL MAYBURY, OF MONTCLAIR, NEW JERSEY.

BRUSH-SUSPENDING DEVICE.

1,312,178.

Specification of Letters Patent. Patented Aug. 5, 1919.

Application filed August 24, 1917. Serial No. 187,937.

To all whom it may concern:

Be it known that I, HOWARD H. HILL, a citizen of Great Britain, and a resident of Montclair, in the county of Essex and State 5 of New Jersey, have invented certain new and useful Improvements in Brush-Suspending Devices, of which the following is a specification.

This invention relates to a device of novel 10 construction which is adapted to be fitted into a brush head and by means of which the brush may be suspended from the rim of a vessel containing water or other liquid, into which the bristles are to be immersed. 15 By thus suspending the brush, the bristles are relieved from the function of partly sustaining the weight of the brush, which weight is apt to bend and permanently injure the same.

20 The drawing shows the invention applied to a paint brush, but it is equally applicable to brushes of other characters.

In the accompanying drawing:

Figure 1 is a side elevation, partly in 25 section, of a paint brush embodying my invention;

Fig. 2, a detail of the suspending means;

Fig. 3, a cross section on line 3—3 Fig. 2, and

30 Fig. 4, a front view of the suspending means.

The brush head 1 having handle 2, and carrying the bristles 3, is encompassed by a ferrule 4 as usual. Head 1, is provided 35 with a laterally opening bore, lined with a tubular casing constituting a bushing 5. Within this bushing is free to slide a suspending member consisting of a shank 6, and a head 7, mounted on the outer end of said 40 shank, so that said head may be readily grasped. Shank 6 is made of resilient material and is doubled at its inner end to form a hook 8, which by bearing against the bushing, will frictionally sustain the suspending member in its advanced or retracted 45 position. The bight of the hook is traversed by a pin 9, extending diametrically through the bushing, and placed at a suitable distance from the inner end thereof, said pin 50 constituting a stop that is carried by the bushing and limits the play of the suspending member within the latter.

In practice, the suspending member is pulled out by means of its head 7, and pro-

jected over the rim 10 of the can or other 55 receptacles into which the brush is to be steeped. When the brush is to be re-used, it is lifted off the can, and the suspending member is pushed into the head.

It will be seen that by my invention, neat 60 and convenient means are furnished for suspending the brush, which means are readily operable, and do not in any manner interfere with the normal function of the brush.

Moreover, by the construction described, the entire suspending device forms a whole which may be introduced into the brush head in an assembled condition, thus dispensing with the necessity of building up 70 said device within said head. Finally, the bushing constitutes a smooth and firm bearing surface for the end of the hook 8, while the suspending member is being advanced or retracted. Through the action of the pin 75 9 or its equivalent upon the hook 8 under an outward pulling force upon the shank 6, said hook 8 is arranged to be restored into proper frictional engagement with the inner surface of the bushing 5, if for any reason 80 this should be necessary.

I claim:

1. A device of the character described comprising a tubular casing arranged to be transversely inserted into a brush and having 85 an axial length less than the transverse width of said brush, a suspending device comprising a shank engaging the inner surface of said tubular casing and a resilient member frictionally engaging the inner 90 surface of said tubular casing, said suspending device being slidable out of said bushing and into the same and being entirely contained therein in its inner position, a head carried 95 by said shank and located exteriorly of the brush and arranged to arrest the inward movement of said suspending device, and a stop carried by said tubular casing whereby the outward movement of said suspending device is arrested.

2. The combination of a brush having a bore extending transversely into the same and terminating at an intermediate point therein, a bushing lining said bore, a suspending device comprising a shank and a 105 resilient member frictionally engaging the inner surface of said bushing, said device being slidable out of said bushing and into

the same and being entirely contained there-
in in its inner position, a head carried by
said shank and located exteriorly of the
brush and a stop carried by said bushing
5 whereby the outward movement of said de-
vice is arrested, said resilient member being
arranged to be restored into proper fric-

tional contact with said bushing by the ac-
tion of said stop under an outward pulling
force upon said shank continued after the 10
outward movement of the device has been
arrested.

HOWARD H. HILL.
